UNITED STATES PATENT OFFICE

LAWRENCE JONES, JR., OF LOUISVILLE, KENTUCKY, ASSIGNOR TO PEERLESS MANUFACTURING COMPANY, OF LOUISVILLE, KENTUCKY, A CORPORATION OF DELAWARE

FIREPLACE DAMPER

Application filed March 28, 1928. Serial No. 265,265.

This invention relates to improvements in fireplace dampers of the class disclosed in Letters Patent No. 1,011,598, granted December 12, 1911, to W. E. Fitch; and the fundamental purpose of the invention is to adapt such dampers to the various conditions that are met in their installation.

Dampers of the class referred to, and which are commonly known as "dome dampers," are designed to be built into the masonry of the chimneys, usually immediately above the fireplace openings, but at times up inside the chimney a material distance above the fireplace. With some mantel constructions it is desirable to project the operating mechanism of the damper door through the front wall of the chimney above the fireplace opening, while in other cases this arrangement is impractical, or objectionable for aesthetic reasons, because of the particular mantel design.

More specific objects of the invention are to provide a dome damper that is suitable for all installations and which has provisions for equipping it with various kinds of operating mechanisms to meet the different conditions above set forth; to provide efficient, yet simple and inexpensive operating mechanisms consisting of a minimum number of parts that add little to the cost of the unit, and to make the operating mechanisms of such character that they can be applied to the damper after the body of the damper has been built into the masonry of the chimney. As a result of my improvements, dealers are enabled, for a relatively small investment, to carry a supply of dampers that satisfactorily meet all requirements.

A construction through which the foregoing objects are realized is illustrated in the accompanying drawings wherein Fig. 1 is a bottom plan view of a dome damper incorporating my improvements; Fig. 2 is a similar view of the damper door; Fig. 3 is a top plan view of the damper body; Fig. 4 is a perspective view of a bracket that is used in two of the operating mechanisms; Fig. 5 is a similar view of a latch plate used in the so-called "ratchet" mechanisms; Fig. 6 is a central longitudinal section through

the body of the damper, showing it built into the masonry of a chimney and equipped with the ratchet mechanism for swinging the damper door and holding it in various adjusted positions; Fig. 7 is a transverse section through the damper and the adjacent portion of a chimney, the damper door being in closed position and equipped with the ratchet operating mechanism; and Fig. 8 is a view, similar to Fig. 7, showing the damper equipped with a cam or so-called "worm" operating mechanism.

The body of the damper is designated generally by the reference numeral 1 and it consists of an upwardly tapering dome comprising a front wall 2, a rear wall 3, and end walls 4 and 5. A horizontal flange 6 extends along the lower edge of the rear wall 3 and the corresponding edges of the end walls 4 and 5 and joins at the front a relatively wide horizontal flange that is designated 7 and serves as an arch-bar for the fireplace opening when the damper body is built into the chimney immediately above the fireplace opening. The end wall 5 is formed with a pocket 10 that is adapted to accommodate the worm type of operating mechanism when conditions make its use desirable.

The damper door 12 is in the nature of a flat plate having an offset lip 13 that extends along its rear edge and part way across its ends, the door having an extension 14 at one end which serves as a closure for the pocket 10. Trunnions 15 and 16 extend from the ends of the door 12, and the upper edges of the end walls 4 and 5 of the damper body have recesses within which the respective trunnions are adapted to rest. The trunnion 16 is held within the recess of the wall 5 against upward displacement by a plate 17 that is suitably secured to said wall, as by bolts 18, and, as best shown in Fig. 6, the middle portion of said plate is inclined upwardly and inwardly so as to permit the opposite end of the door to be raised and the door shifted laterally thereby to withdraw the trunnion 16 from the pocket in the wall 5. This arrangement enables the door to be inserted and removed from a

position below the damper body after the latter has been installed.

The front and rear walls of the pocket 10 have apertures through which a shaft 20, that is preferably square in cross section, is adapted to be extended, and 21 is a worm that is arranged for mounting upon the said shaft within said pocket. The worm has a spiral slot 22 within which a stud 23 of a bracket 24, shown in perspective in Fig. 4, is adapted to be engaged when said bracket is secured to the door 12 by bolts or other fastening means engaged through holes 25 in said door, such an arrangement being shown in dotted lines in Fig. 1, and in full lines in Fig. 8. The door is preferably marked with the word "Worm" adjacent the holes 25 to indicate that the bracket 24 is to be applied in this position when operating mechanism of the worm type is to be used. The shaft 20 is extended through an opening in the front wall of the chimney, and beyond said wall has secured to it an operating handle 26. By turning this handle the worm 21 is rotated to shift the stud 23 of the bracket forwardly and rearwardly thereby to swing the door 12 on its trunnions between open and closed positions. By reason of the nature of the worm drive the door is held in any position to which it is adjusted.

Where, for reasons already stated, it is impractical or undesirable to extend the shaft 20 through the front wall of the chimney above the fireplace opening, the operating mechanism above described is replaced by a so-called "ratchet" mechanism, the same being illustrated in Figs. 1, 6 and 7. In adapting the device to the use of this mechanism, the bracket 24 is secured to the door 12 by passing its connecting means or bolts through holes 28, alongside which the word "Ratchet" appears on the door. The rear end of a ratchet bar 30 has an aperture through which is adapted to be engaged the stud 23 of the bracket 24, said stud having a hole 31 through which a cotter pin or other holding means 32 is adapted to be extended. A notched latch plate 33, shown in perspective in Fig. 5, is adapted to be secured to the underside of the arch-bar 7 in such a position that the ratchet bar 30 may play freely through the slot thereof, the underside of the ratchet bar having notches 35 located at suitable distances apart along its lower edge for cooperation with the edge of the ratchet plate below the slot thereof. A handle 36 is fastened to the forward end of the latch bar. By lifting said handle 36, the bar may be released from holding engagement with the latch plate 33 and shifted inwardly and outwardly to swing the door 12 on its trunnions, and the door is adapted to be held in given positions by the engagement of the notches 35 with the latch plate.

When the damper is installed in a chimney

a distance above the top of the fireplace opening, the worm and ratchet mechanisms are discarded and chains are connected to lugs 38 that are formed on the underside of the damper door near the left hand end thereof, as the parts are viewed in Figs. 1, 2 and 6, and the door bears the word "Chain" adjacent said lugs. The chains (not shown) depend into the fireplace opening where they are readily accessible for the purpose of opening and closing the damper door.

Having thus described my invention, what I claim is:—

1. A damper of the class described comprising a body designed to be built into the masonry of a chimney, a closure movably supported thereby, and adapted to be operated by any one of a plurality of operating mechanisms, and an element for attachment to the closure in either of two positions for effecting operative connections between it and one of the selected mechanism which element is common to both mechanisms.

2. A damper of the class described comprising a body designed to be built into the masonry of a chimney, having an elongated opening therein, a door for said opening pivotally connected to the body on substantially the longitudinal axis of said opening, a bracket adapted to be secured to said door in either of two positions, said door being provided with means for connecting the bracket in either of the two positions thereon to accommodate one of two different types of operating means adapted to be used therewith and marks on the closure adjacent the places where said bracket is to be attached to indicate the character of the respective mechanisms to be associated therewith when the bracket is secured in that place.

In testimony whereof, I hereunto affix my signature.

LAWRENCE JONES, JR.
